CLAIM

I claim the ornamental design for a clip, as shown.

DESCRIPTION

FIG. 1 is a front elevation view of a clip.

FIG. 2 is a back elevation view thereof.

FIG. 3 is a side elevation view thereof, where the left and right side views are identical.

FIG. 4 is top plan view thereof.

FIG. 5 is bottom plan view thereof.

FIG. 6 is an upper back perspective view thereof; and, FIG. 7 is a lower front perspective view thereof.
